CLAIM

The ornamental design for a diving mask as shown and described.

DESCRIPTION

FIG. 1 is a perspective view of a diving mask according to the new and ornamental design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines illustrate portions of the diving mask that form no part of the claim.

1 Claim, 5 Drawing Sheets
